UNITED STATES PATENT OFFICE.

GEORGE F. ATWOOD, OF NEWARK, NEW JERSEY, ASSIGNOR TO WESTINGHOUSE LAMP COMPANY, A CORPORATION OF PENNSYLVANIA.

MACHINE FOR MOUNTING INCANDESCENT-LAMP FILAMENTS.

1,145,660.

Specification of Letters Patent.

Patented July 6, 1915.

Application filed January 31, 1910. Serial No. 541,108.

To all whom it may concern:

Be it known that I, GEORGE F. ATWOOD, a citizen of the United States, and a resident of Newark, in the county of Essex and State 5 of New Jersey, have invented a new and useful Improvement in Machines for Mounting Incandescent-Lamp Filaments, of which the following is a specification.

My invention relates to machines for use 10 in the manufacture of incandescent lamps, and it has for its object to provide a machine whereby filaments may be securely and expeditiously applied to the leading-in wires of lamps or to other supports therefor.

15 The invention is particularly useful in the construction of the lamp that is set forth in Patent No. 976,248, in which lamp, the end portions of the filament are wound around, or otherwise embrace, the end portions of 20 the leading-in wires, and the extremities of which are fused, or are otherwise joined, to the extremities of the leading-in wires.

25 Figure 1 of the accompanying drawings is a side view of a machine constructed in accordance with my invention. Fig. 2 is a view, in end elevation, of the same machine. Fig. 3 is an enlarged side view of one of the parts of the machine. Fig. 4 is a face view of the same part, also in enlargement, and 30 Fig. 5 is a perspective view of the supporting clamp for the lamp stems.

The machine comprises a rod or standard 1 having a bearing block 2 at its upper end in which a shaft 3 and a sleeve 4 that 35 rounds the shaft are mounted for independent rotation, the sleeve and the shaft being separated by means of an insulating bushing 5. The shaft 3 and the sleeve 4 are driven, respectively, by means of fiber or other suitable insulating pulleys 6 and 7 that are operatively connected, by means of belts 8 and 9, to other pulleys 10 and 11 that are rotatably mounted in bearing blocks 12 carried by the standard 1 and may be operated manually, or otherwise, as desired.

45 Mounted upon the end of the sleeve 4, opposite the pulley 7, is a frame comprising a central block 14, that is secured to the sleeve 4, and rods 15 and 16, that project from opposite sides of the block 14. Upon the rod

15, and adjustable longitudinally thereof, is a block 17 having a socket 18 for the reception of a supporting pin 19 of a work-holder or clamp 20, (Fig. 5), the work in the present instance consisting of the stem 21 of an incandescent lamp through which leading-in wires 22 and 23 extend. The work-holder 55 consists of a block 24 having a V-shaped slot or recess, in which the cylindrical portion of the stem 21 is seated, and a spring clip 25 for 60 clamping or securing the stem in the V-shaped seat. The rod 16 carries a block 26 that is adjustable longitudinally thereof and supports a wire mandrel 27, over which a filament 28 is bent during its application to 65 the leading-in wires 22 and 23.

Mounted upon the end of the shaft 3, opposite the pulley 6, is a disk or plate 30, at the center of which a quartz or other suitable insulating rod 31 is secured, said rod 70 being centrally apertured for the reception of the upper laterally projecting end of the leading-in wire 22. The rod 31 serves as a centering or positioning member for the stem and leading-in wires of the lamp, and 75 also as a steadyng means for the free end of the wire 22. Rotatably mounted upon the face of the plate 30, and at one side of the rod 31, is another quartz or other insulating rod or mandrel 32 having a pulley or brake 80 wheel 33 secured thereto adjacent to the plate 30. A cord or band 34, that passes over the pulley or brake wheel, is secured, at one end, to a helical tension spring 35, whereby it is maintained taut, and at its 85 other end to a screw 36, whereby its tension may be regulated. Projecting from one face of the pulley 33, parallel and adjacent to the rod or mandrel 32, is a pin 37 between which and the mandrel 32 one end of the 90 filament is held during its application to the leading-in wires 22 and 23.

Interposed between the member 30 and the block 14 is a helical compression spring 38 whereby the shaft 3 and its associated 95 parts are caused to rotate simultaneously with the sleeve 4 when the actuating force is applied only to the pulley 7. Because of the greater weight and inertia of the sleeve 4 and its associated parts, however, the 100

spring 38 is ineffectual to cause rotation of the sleeve 4 and its associated parts when the actuating force is applied solely to the pulley 6.

5 The shaft 3 and the sleeve 4 and their associated parts are insulated from each other in order that currents may be independently supplied thereto. Current may be conducted to the shaft 3 by means of a resilient strip 10 or arm 39 that bears against one end thereof and is connected to a suitable source of current, such as a battery 40, the current being conducted through the shaft 3 and the member 30 to the pin 37, which, accordingly, constitutes a circuit terminal.

In the operation of the machine, a lamp stem is placed in the holder with the laterally bent extremity of one of the leading-in wires 22 inserted in the end aperture in the 20 positioning and supporting member 31. One end of the filament 28 is then inserted in the space between the pin 37 and the mandrel 32, the pin 37 at this time being revolved so as to be at the greatest distance 25 from the rod 31. If the filament is composed of tungsten, or of other material that must be heated in order to render it pliable, its other end is connected to the other terminal of the battery 40. While the 30 filament is in a pliable condition, the pulley 10 is rotated manually to wind the filament around the laterally projecting end portion of the leading-in wire 22, the mandrel 32 being rotated and the pin 37 revolved 35 by the tension thus placed upon the end portion of the filament, which is thereby unreeled for application to the leading-in wires. This feature of the machine should be noted particularly, since, by means thereof, the filament may be wound around the leading-in wire 22 without being subjected 40 to undue tension and without being required to slip around the leading-in wire to permit of applying a sufficient number of convolutions thereof thereto. The cord 34 serves as a brake for the movements of the parts 32 and 37, and tension upon the filament may be regulated by means of the screw 36. The frame 14—15—16 is next rotated so as to 45 revolve the lamp stem and the mandrel 27 and to permit of wrapping the filament around the mandrel, of bringing it into engagement with an intermediate support 41, and of winding it around the laterally projecting portion of the leading-in wire 23, the member 30 being rotated simultaneously 50 with the frame because of the pressure exerted upon it by the spring 38. After the filament has been thus applied to its supports, the free ends of the leading-in wires 55 22 and 23 may be connected to one terminal of an electrical circuit (not shown), and the other terminal may be applied successively to the adjacent extremities of the filament

and leading-in wires, for the purpose of fusing the said parts together and making good electrical connections between them. If desired, the adjacent extremities of the filament and the leading-in wires may be brought into intimate electrical contact by covering them with a layer of conducting paste.

If the filaments are of such a character that they are oxidized when heated in air for the purpose of rendering them pliable, 75 the whole apparatus may obviously be introduced into a vessel filled with an inert gas.

It is obvious that the apparatus lends itself to the mounting of two or more filaments at a time upon a stem. 80

I claim as my invention:

1. A machine of the character described comprising a steadyng and positioning member for the work, a yielding clamp, a work-holder, and means for mounting the 85 yielding clamp and work-holder for independent revolution around the steadyng and positioning member.

2. A machine of the character described comprising a steadyng and positioning member for the work, a rotatable mandrel, a pin adjacent to the mandrel, means for mounting the pin for revolution around the mandrel, a work-holder, and means for mounting the mandrel and the work-holder 95 for revolution around the steadyng and positioning member.

3. A machine of the character described comprising a steadyng and positioning member for the work, a rotatable mandrel, a 100 pin adjacent to the mandrel, means for mounting the pin for revolution around the mandrel, a work holder, and means for mounting the mandrel and the work-holder for independent revolution around the 105 steadyng and positioning member.

4. A machine of the character described comprising a steadyng and positioning member for the work, a rotatable mandrel, a pin adjacent to the mandrel, a brake to 110 control the rotative movement of the mandrel, a work holder, and means for mounting the mandrel and the work-holder for revolution around the steadyng and positioning member. 115

5. A machine of the character described comprising means for steadyng and positioning the work, means for yieldingly clamping a part of the work, means for holding another part of the work, and means 120 for mounting the yielding clamping means and the said holding means for independent revolution around the steadyng and positioning means.

6. Apparatus for applying a wrapping 125 to a cylindrical member comprising means for positioning the cylindrical member, a clamp for one end of the wrapping, spaced

from said positioning means and revoluble
thereabout, means for revolving said clamp
about said positioning means, and resilient
means for allowing said clamp to approach
5 said positioning means as the wrapping is
applied to the cylindrical member.

In testimony whereof, I have hereunto

subscribed my name this 20th day of Janu-
ary, 1910.

GEORGE F. ATWOOD.
